UNITED STATES PATENT OFFICE.

GEORGE W. CANNON, OF POUGHKEEPSIE, NEW YORK.

HAND-ELEVATOR.

SPECIFICATION forming part of Letters Patent No. 408,693, dated August 13, 1889.

Application filed December 21, 1887. Serial No. 258,606. (No model.)

To all whom it may concern:

Be it known that I, GEORGE W. CANNON, a citizen of the United States, residing at Poughkeepsie, in the county of Dutchess and State of New York, have invented a new and useful Hand Elevator or Hoist, of which the following is a specification.

My object is to produce an elevator of simple construction and easy operation, so graduated as to raise easily and safely any weight, from one to fifteen hundred pounds. I have heretofore obtained a patent, No. 361,263, for a dumb-waiter adapted to raise with facility like loads; but this invention is of different construction and operation. I secure greater power by introducing gear-wheels and so arranging my ropes that my operating and hoist ropes supplement each other in holding the load in case of the breaking of either rope, and so long as either rope remains intact the car cannot fall. By a brake-rope at the side I hold the load in any position.

My invention consists in my peculiar arrangement of hoist-wheel axle, gear-wheels, weight wheel, pulleys, hoist-rope, and endless power-rope to produce a motion varying from one to six to one to ten between the car and a point in the power-rope.

I will now describe my invention in reference to the drawings.

Figure 1 is a front view, slightly in perspective, exhibiting the operative parts in position. Fig. 2 is a plan view of the top of the elevator.

A is the power-wheel; B, the large wheel. C, D, H, L, and G indicate small pulleys; A', the larger standards, A'' the standard of the wheel B, and A''', the ordinary standards of the small pulleys; F, the shaft; J, the small cog-wheel attached to the shaft; E, the large cog-wheel; e, the groove-wheel on the side of the large cog-wheel, over which the hoist-rope passes.

K shows the top of the elevator, to which are screwed the standards supporting the operative parts.

I indicates the brake, which is operated against the power-rope by the cord T.

Q is the endless power-rope by which the elevator is operated.

R is the hoist-rope, one end of which is fast-

ened to the top of the elevator-car at T', and it passes up over the large groove on the side of the large cog-wheel and under the small pulley S, over the pulley L, and down to the 55 snatch-block holding the pulley M.

M is the pulley in the snatch-block.

N is a weight.

The endless power-rope Q passes up on one side of the elevator and down on the other, 60 and may be operated by being pulled by the hand on either side.

The weight well or space for its ascent and descent may, by means of the pulleys, be placed on the rear or right or left side, as convenience of space may require in construction. The power-rope Q passes on the left side over the large wheel A, under the pulley C, over the pulley D, down through top K and under the pulley M, up through top K and over the 70 pulleys H and G, down to and under the pulley O and up and over the large pulley B, and down on the right side of the elevator and around the bottom to its ascent on the left side.

The wheel A, I prefer to make about ten 75 times as large as the cog-wheel on its shaft J, and cog-wheel E about three times as large as shaft J, and its grooved wheel e, attached to it, is about two-thirds the size of wheel E. These latter wheels may be placed on standards, as shown, or journaled on the back legs of the standards A'. The guide-wheel B, I prefer to make about twelve to fifteen inches in diameter, and the other pulleys C, D, H, G, O, L, and S about six inches in diameter, and for all ordinary loads my power-wheel A about thirty inches in diameter. The size of A and the cog-wheels J, E, and e, and the weight of N may be changed to adapt the elevator to different loads and powers. The 90 cam-brake I is placed on the shelf or top K, and can easily be operated by hand applied to the cord T.

To operate my elevator, pull down on the left side of rope Q, which tightens the rope R, 95 lifts the cage, and the descending weight N takes up the slack in the endless rope as the car is lifted, and in case the hoist-rope R should break at any time the weight coming on the operating-rope at O would cause the 100 car to impinge in its grooves and stop the load from falling.

Having thus described my invention, what I claim, and desire to obtain Letters Patent for, is—

1. The combination of an elevator-car with a hoist-wheel A, axle F, cog-wheels J and E, and groove-wheel e, counterpoise-weight N, brake I, pulleys M, L, B, C, D, II, G, and S, hoist-rope R, and power-rope Q, as shown and described.
2. The combination of the elevator-car with

the hoist-wheel A, axle F, cog-wheels J and E, wheel e, counterpoise-weight N, pulleys M, L, B, C, D, II, G, and S, the hoist-rope R, and endless power-rope Q, as shown and described.

GEORGE W. CANNON.
